US00D868027S

(12) **United States Design Patent** (10) **Patent No.:** **US D868,027 S**
Paterson (45) **Date of Patent:** **** Nov. 26, 2019**

- (54) **COMMUNICATIONS HEADSET OR HEADPHONE**
- (71) Applicant: **Plantronics, Inc.**, Santa Cruz, CA (US)
- (72) Inventor: **Nicholas W Paterson**, Santa Cruz, CA (US)
- (73) Assignee: **Plantronics, Inc.**, Santa Cruz, CA (US)
- (**) Term: **15 Years**
- (21) Appl. No.: **29/653,425**
- (22) Filed: **Jun. 14, 2018**
- (51) LOC (12) Cl. **14-01**
- (52) U.S. Cl. **USPC D14/205; D14/206; D14/226**
- (58) **Field of Classification Search**

OTHER PUBLICATIONS

Paterson et al., "Communications Headset or Headphone," Design U.S. Appl. No. 29/606,288, filed Jun. 2, 2017 (12 pages).

Primary Examiner — Paula Allen Greene

(57) **CLAIM**

The ornamental design for a communications headset or headphone, as shown and described.

DESCRIPTION

FIG. 1 is a front-right perspective view of a communications headset or headphone showing my new design;

FIG. 2 is a back-left perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines showing the unclaimed features form no part of the claimed design.

1 Claim, 8 Drawing Sheets
